UNITED STATES PATENT OFFICE.

MAJOR ROMEYN JEWELL, OF ROCHESTER, NEW YORK, ASSIGNOR TO THE
OFFICE SPECIALTY MANUFACTURING COMPANY, OF SAME PLACE.

FILE-BOX.

SPECIFICATION forming part of Letters Patent No. 408,979, dated August 13, 1889.

Application filed February 6, 1889. Serial No. 298,879. (No model.)

To all whom it may concern:

Be it known that I, MAJOR ROMEYN JEWELL, of Rochester, in the county of Monroe and State of New York, have invented certain Improvements in File-Boxes, of which the following is a specification.

This invention has reference to that class of boxes which are commonly used for the storage of letters transferred from letter-files in which they are arranged in flat form and commonly known in the art as "transfer" or "storage" boxes.

The aim of the invention is to provide an inexpensive box which may be shipped and stored in a flat or knockdown form and speedily set up in rigid form by the user; and to this end it consists, essentially, in a series of flat sections hinged together and provided at certain of their corners with metallic fastening devices, which are adapted to be united readily when the box is adjusted for use.

In the accompanying drawings, Figure 1 is a perspective view showing my box in its flat or knockdown condition. Fig. 2 is a perspective view of the same as it appears in condition for use. Fig. 3 is a cross-section of the box as it appears when closed. Figs. 4 and 5 are perspective views of the two members constituting a corner fastening. Fig. 6 is a perspective view showing the manner in which the two parts of the fastening are brought together. Fig. 7 is a perspective view showing the same when completed. Fig. 8 is a modification of the fastening devices.

In proceeding to construct my box, which is of flat rectangular form with a hinged side or top, I provide a rectangular bottom sheet *a* and a top sheet *b* of corresponding size. To the respective edges of the bottom sheet *a*, I hinge the two side pieces *a'* and *a''* and the two end pieces *a³* and *a⁴*, these parts being made of such size and form that when turned to a vertical position they will unite at the corners and form the four walls of a box. To the outer edge of the rear side *a²*, I hinge one edge of the top *b*, and to the outer edges of the top I hinge the two end strips *b'* *b''* and the front strip *b³*, so formed and arranged that when turned at right angles to the plane

of the back they will form a rim or flange around its three edges.

The hinge-joints between the several parts are commonly formed by strips of cloth, leather, or other suitable material pasted over the joints after the manner commonly practiced in book-binding and in the construction of pasteboard boxes.

For the purpose of firmly uniting the walls *a² a³ a⁴* of the box and maintaining them in their perpendicular position, and for uniting in like manner the edges *b' b'' b³* of the top, I provide metallic fastening devices, which are to be attached to the respective members of the box at the time of its manufacture and while it is in flat form, these fastenings being adapted to be bent and interlocked by hand when the box is erected for use. I prefer to construct these fastenings in the form shown in Figs. 4 and 5, each consisting of two wire staples *d* *d'*, having their ends bent at right angles, so that they may be secured by passing these ends through the sheets from one side and bending them down on the opposite sides. I apply a staple *d* at the rear edges of the end sections *a³* and *a⁴*, allowing them to project beyond the same, as shown, and I apply to the opposite ends of the back *a²* the corresponding staple *d'* in such position that upon first turning the ends to an upright position, and then turning the back upward, the staples *d* will pass through the staples *d'* in the manner shown in Fig. 6, after which I bend the staple *d* backward and downward into a hook form, as shown in Fig. 7.

In this manner I maintain a close and rigid union at the corner of the box, securing the three walls *a² a³ a⁴* in their vertical positions. The top *b* has the two ends of its edge *b³* provided with staples *d'*, and the ends *b'* and *b''* provided with staples *d*, so that when these edges are turned up to their operative position they may be united by means of the staple in the same manner that the corners of the box or body were united. The result of these simple operations is a box such as shown in Fig. 2, having three rigid walls, the hinged front wall *a'* and a hinged lid, which latter serves not only to close the top and the bottom, but by engaging over

the hinged wall a' to hold the latter in position.

In the box thus constructed I propose to employ filing or securing devices of any suitable construction to retain the sheets in position, if desired. These devices, constituting no part of the invention, are not illustrated herein.

While it is preferred to construct the corner fastenings of wire, it is to be understood that they may be constructed of sheet metal in the form shown in Fig. 8, or any similar form, if preferred. As herein shown, one part d' is provided with a slot and the other part d with a tongue adapted to be passed therethrough and bent down on the outside. The two parts will be provided with prongs d^2 and d^3 , or equivalent means for securing them permanently to the box.

Having thus described my invention, what I claim is—

1. A knockdown box for the filing of papers and for similar purposes, consisting of a

series of flat sections hinged together at their edges and provided at their corners with metallic fastening devices adapted to be bent and interlocked.

2. The herein-described box, consisting of the bottom sheet and the side walls hinged thereto, the top sheet and the edge strips hinged thereto, and the metallic fastening devices d and d' applied at the corners and adapted to be interlocked, as described, to hold the box in operative position.

3. An improvement in knockdown boxes, the metallic staples d and d' , applied to the adjacent sides of the box and adapted to be bent and interlocked, substantially as described.

In testimony whereof I hereunto set my hand, this 4th day of April, 1888, in the presence of two attesting witnesses.

MAJOR ROMEYN JEWELL.
